UNITED STATES PATENT OFFICE.

GEORGE W. HOLMES, OF COUNCIL BLUFFS, IOWA.

CAR-COUPING.

SPECIFICATION forming part of Letters Patent No. 259,153, dated June 6, 1882.

Application filed March 23, 1882. (Model.)

To all whom it may concern:

Be it known that I, GEORGE W. HOLMES, of Council Bluffs, in the county of Pottawattamie, and in the State of Iowa, have invented 5 certain new and useful Improvements in Car-Couplings; and I do hereby declare that the following is a full, clear, and exact description thereof, reference being had to the accompanying drawings, and to the letters of reference 10 marked thereon, making a part of this specification.

This invention relates to certain improvements in car-couplers; and it has for its objects 15 improved means whereby the link may be adjusted to enter the draw-heads without necessitating the entrance of the train-men between the approaching cars, and thus endangering their lives, as more fully hereinafter specified. These objects I attain by the devices and mechanism 20 illustrated in the accompanying drawings, in which—

Figure 1 represents a side elevation of the draw-heads of two cars to be coupled and my link-adjusting device, and Fig. 2 a detached 25 view of the link-adjusting device.

The letter A indicates the draw-heads, which are of the usual construction.

B designates a lever-frame fulcrumed at opposite sides of a transverse block, C, located 30 immediately above the draw-head on the end of the draw-bar or other convenient portion of the car. The said lever-frame is composed, preferably, of a bar of wrought metal, bent, as indicated, so as to form a support, E, for the link, and an inclined arm, F, against which the 35 draw-head of an approaching car is adapted to bear so as to trip the lever when the cars meet.

The letter G indicates the link, which is of the ordinary construction, and H and H' the usual coupling-pins.

The operation of my invention is as follows: The link is inserted in one of the draw-heads, as indicated in Fig. 1 of the drawings, and the coupling-pin is inserted in the usual manner. The lever-frame is then elevated so as to hold 45 the link in a horizontal position, so as to properly enter the draw-head of the opposite car. When the cars meet the inclined arm of the lever-frame is pressed downward by the draw-head of the opposite car, so as to force it out 50 of the way, and the coupling-pin H' is then dropped into place. The short arms I of the lever-frame limit its upward movement and serve to render it conveniently adjustable to hold the link in a proper horizontal position. 55

Having thus described my invention, what I claim, and desire to secure by Letters Patent, is—

In combination with the draw-head, the bifurcated frame B, consisting of a bar of metal 60 bent so as to form a support, E, for the link G, and inclined arm to guide the link to the draw-head, and the transverse block to which the frame is pivoted, the frame being provided with arms I to limit its movement, substantially as specified.

In testimony whereof I affix my signature, in presence of two witnesses, this 13th day of March, 1882.

G. W. HOLMES.
